CLAIM

I claim the ornamental design for a knife handle, as shown and described.

DESCRIPTION

FIG. 1 is a perspective view of a knife handle showing the claimed design;

FIG. 2 is a side elevation view of the claimed design.

FIG. 3 is a top elevation view of the claimed design.

FIG. 4 is a front elevation view of the claimed design; and,

FIG. 5 is a rear elevation view of the claimed design.

The broken lines in the drawings are for illustrative purposes only and form no part of the claimed design.
